UNITED STATES PATENT OFFICE

146,998

DESIGN FOR A GARMENT HANGER

Margaret H. Townsend and Robert C. Townsend,
Fort Worth, Tex.

Application May 28, 1946, Serial No. 130,174

Term of patent 14 years

(CL. D80—8)

To all whom it may concern:

Be it known that we, Margaret H. Townsend and Robert C. Townsend, citizens of the United States of America, residing at Fort Worth, in the county of Tarrant and State of Texas, have invented a new, original, and ornamental Design for a Garment Hanger, of which the following is a specification, reference being had to the accompanying drawing, forming part thereof.

We claim:

The ornamental design for a garment hanger, substantially as shown.

MARGARET H. TOWNSEND.
ROBERT C. TOWNSEND.
